UNITED STATES PATENT OFFICE.

WILLIAM T. SAPP, OF HINSON, FLORIDA.

RAIL-JOINT.

1,076,320.

Specification of Letters Patent.

Patented Oct. 21, 1913.

Application filed March 18, 1913. Serial No. 755,243.

To all whom it may concern:

Be it known that I, WILLIAM T. SAPP, a citizen of the United States, residing at Hinson, in the county of Gadsden and State of Florida, have invented new and useful Improvements in Rail-Joints, of which the following is a specification.

The present invention relates to improvements in rail joints.

10 In carrying out my invention it is my purpose to provide a rail joint which will effectively support the meeting ends of the rail to prevent the sinking movement of either of the rails incident to the rolling stock passing thereover, as well as to effectively overcome any tendency of the lateral movement of the rails at the joint.

A further object of the invention is the provision in a rail joint, of rail securing 20 means which shall be connected directly with the ties as well as with the rail ends, but which will permit of the rails resting upon the said ties so that while the said rails at their joints are rigidly supported, the 25 portions of the rails directly beyond the ends thereof resting upon the ties will be allowed the resiliency afforded by the ties, and danger of the chipping of the rails or the breakage of the rail ends is entirely and effectively overcome.

It is a still further object of the invention to provide rail connecting members which shall have a locking engagement one with the other, so that accidental displacement or 35 separation of the said members will be effectively prevented.

With the above recited objects in view, and others which will appear as the nature of the invention is more fully understood, 40 the improvement resides in the construction, combination and operative arrangement of parts set forth in the following specification and falling within the scope of the appended claims.

45 In the drawings: Figure 1 is a view of a rail joint constructed in accordance with the present invention, Fig. 2 is a transverse sectional view on the line 2—2 of Fig. 1, Fig. 3 is a similar sectional view on the line 3—3 50 of Fig. 1, Fig. 4 is a horizontal sectional view on the line 4—4 of Fig. 1, Fig. 5 is a perspective view of one of the joint members, and Fig. 6 is a similar view of the co-acting joint member.

55 The rails R—R have their co-acting ends disposed between two ties T—T. The rails

are of the ordinary construction, and have their webs provided with a plurality of bolt-receiving openings. The joint includes a pair of co-acting members which are designated by the numerals 1 and 2 respectively.

The member 1, which will hereinafter be referred to as the chair member, includes an angular side 3, the inner face of which corresponds to the fishing spaces of the rails R upon the outer sides of the said rails. The vertical member 4 of the angular side 3 is provided with a plurality of openings 5 which coincide in number and which align with the bolt openings in the webs of the rails. The side 3 is centrally formed with reinforcing member 6 which is disposed upon the outer face of the said side and which is of an angular shape corresponding to the shape of the said side 3. The upper edge 75 of the vertical member 4 of the side 3 conforms to the shape of the underfaces of the heads or balls of the rail ends adapted to engage with the said balls of the rails when the chair is arranged upon the rails. The 80 reinforcing member 6 is adapted to have its upper edge also engaged beneath the balls of the rails R directly at the juncture of the ends of the said rails, and the reinforcing member 6 is of a sufficient width to effectively receive and support the said heads at their meeting ends. The lower and angular portion of the member 6 is formed with a lip 7 which depends below the outer edge of the lower and angular portion 8 of the side 3. This lip is adapted to contact with the outer edges of the base flanges of the rails at the joint of the said rails, the lip being of a width equaling the width of the remainder of the reinforcing member 6. 95 The angular base member 8 of the side 3 adjacent the ends of said side is formed with extensions 9, the upper walls of said extensions being arranged in a plane corresponding to the angular plane of the outer 100 faces of the base 8 of said side, and integrally formed with the sides of said extensions 9 are transversely arranged plates 10 and 11 respectively. These plates are arranged in parallel spaced relation to each 105 other and have their upper edges arranged a suitable distance below the underface of the angular portion 8 of the chair 1. The plates, while integrally formed with the extensions 9, project a suitable distance beyond the said angular extensions and are 110 provided with an upper connecting wall 12

which is horizontally straight and which is provided with bolt-receiving openings 13. Integrally formed with the angular side 3, the extensions 9 and the outer connecting wall 12 of the plates 10 and 11, are ribs 14 which materially strengthen the extensions 9 and which effectively reinforce the upper wall or connecting member 12 of the plates 10 and 11.

10 The plates 10 and 11 extend a suitable distance beyond the inner face of the side 3 of the chair 1 and the outer and upper edges of the said plates are provided with an integral connecting member 15 which has its inner portion enlarged, as at 16, and the lower face of which being channeled or grooved, as at 17. The plates 10 and 11 are provided with suitable openings 18, and each pair of plates 10 and 11 are spaced away from each other a distance equaling the width of the ties T, so that the said plates are disposed at the opposite sides of said ties, and connected thereto through the medium of securing elements which pass through the openings 18 of the said plates and the openings 13 and 19 formed in the upper or connecting portions 12 and 15 at the ends of the plates. It is to be understood that the upper edges of the plates 10 and 11 are disposed below the upper faces of the ties T, and after the chair 1 has been connected with the ties, as just described, the rails R are positioned upon the ties and have their sides as well as their meeting ends arranged for connection with the chair member 1, as previously described.

The member 2 provides the angular bar or fish plate for the joint. The angular member 2 has its vertical portion 20 arranged so that its upper edge will underlie the balls of the rails, and its inner face at the juncture of said vertical member and the angular portion 21 thereof will contact with the rails at the juncture of the webs and base flanges of the rails. The angular member 3 is also designed to have its inner face at its juncture with the portions 4 and 8 contact with the outer faces of the rails at the juncture of the webs and the base flanges of said rails. The angular portion 21 has its inner face shaped to conform to the upper faces of the base flanges of the rails, which it is adapted to overlie, and the angle bar or fish plate 2 is centrally provided with a reinforcing element 21' which is integrally connected therewith and which is substantially similar to the reinforcing member 6 of the chair 1. The reinforcing element 21', however, terminates a suitable distance below the upper edge of the angle bar 2, so that the flanges of the wheels of the rolling stock, passing over the joint, will not be interfered with. The reinforcing member 21' is formed with a lip 22 which is arranged in a plane with the outer longitudinal edge of said angle

bar and which extends below the said bar, the lip being disposed to contact with the longitudinal edges of the base flanges of the rails at the inner faces of the rails and at the point of meeting of the said rails. The angular portion 21 of the fish plate 2 is formed, adjacent the ends of said fish plate with integrally formed outwardly extending feet 23, and the upper corners of said feet are longitudinally cut away to provide the outer and lower portions of the feet with tongues 24 which are adapted to be received within the groove 17 of the enlarged portions 16 of the connecting member 15 of the plates 10 and 11. The feet are provided with openings 25, the said openings forming passages for securing spikes which enter the ties T. The member 20 of the plate 2 is also provided with openings 26 which equal in number and which align with the openings 18 in the webs of the rails, and the registering openings are adapted to receive suitable bolts 27 which are provided with securing nuts 28.

From the above description the simplicity of the device as well as the means of connecting the device to the rail ends will, it is thought, be perfectly apparent to those skilled in the art to which such inventions appertain without further detailed description.

What I claim is:

1. In a rail joint, the combination with two rail ends, and ties for the ends and arranged at the opposite sides of the meeting edges of the rail ends, a chair member having an angular side adapted to engage with one of the faces of the rail ends, said chair including transversely arranged plates which are integrally formed therewith, and which are arranged in pairs and adapted to straddle and to be secured to two of the ties and to have their upper edges arranged below the faces of the ties, connecting members for the plates, an angle bar, an interlocking connection between the angle bar and the connecting members of the plates, and means for securing the chair and angle bar to the rails and to the ties for the rails.

2. In a device for the purpose set forth, the combination with two rail ends and ties upon which the rails rest, of a rail joint, said joint including a chair having an angular member adapted to engage the fishing space upon one of the sides of the rails, said chair having the base of its angular member extended adjacent its ends, the said extensions being provided with integrally formed transversely arranged plates arranged in pairs, a connecting upper member for the upper edges of the plates, each of said members being provided with a longitudinally extending groove, an angle bar for the opposite faces of the rails, said bar being provided with extending tongues which are adapted to

be received within the grooves of the connecting members of the plates, the said plates adapted to engage two of the ties opposite the meeting ends of the rails and to have their upper edges disposed below the faces of the ties, means for securing the joint to the ties, and means for securing the chair to the angle bar.

3. In a rail joint, the combination with two rails and ties upon which the rails rest, of a chair, said chair including an angle plate adapted to conform to and engage within the fishing space upon one side of the rails, the said angular member being centrally formed with a reinforcement which underlies and engages with the heads of the rails at the meeting ends, the said angle member having its horizontal flange extended adjacent its ends, each of the extending members having a pair of spaced plates which are disposed transversely of the angle member and arranged below said angle member, the said plates adapted to straddle the two ties opposite the meeting ends of the rails and to be secured to the sides of the tie, a connecting member for the upper edges of the ends of the plates, each of said members being provided with grooves, an angle bar for the opposite side of the joint, said angle bar having extensions adjacent its ends provided with tongues which are adapted to be received within the grooves of the connecting members of the plates, means for securing the angle bar to the ties, and means for securing the angle bar to the rails and to the chair member of the joint.
4. In a rail joint, the combination with two ties and two rails resting upon the ties and having their meeting ends disposed centrally between the ties, of a chair having an angular side shaped to conform to the fishing space of the rails upon one of the sides

thereof, said angular side being centrally provided upon its outer face with a reinforcing member which is adapted to contact with the heads of the rails upon their lower faces and at the ends of the rails, the said reinforcing member having a tongue which extends beyond the longitudinal edge of said angular side and which is adapted to abut with the meeting edges of the base flanges of the rails, the said angular side being provided with extensions which project from the edge thereof adjacent the ends of the chair, reinforcing members integrally formed with the angular side and with the extensions, said extensions having laterally extending plates secured to each of the edges of the extensions, the said plates extending beyond and below the angular side of the chair and adapted to engage with and to be connected to the ties, an upper connecting member for the ends of each pair of plates, an angle bar adapted to engage within the fishing spaces of the opposite sides of the rails, said angular bar being centrally provided with a brace reinforcement terminating in a downwardly extending tongue which is adapted to engage with the edges of the base flanges of the rail ends, the said angle bar having its horizontal member adjacent its ends provided with extending tongues, the said tongues adapted to engage the connecting members of the plates, means for securing the angle bar to the ties, and means for securing the angle bar to the rail ends and to the angular side of the chair of the joint.

In testimony whereof I affix my signature in presence of two witnesses.
